UNITED STATES PATENT OFFICE.

ALLAN M. HIRSH, OF MONTCLAIR, NEW JERSEY, AND JOHN C. MITCHELL, OF NEWPORT NEWS, VIRGINIA.

MANUFACTURE OF CONCRETE PIPE.

1,102,584.

Specification of Letters Patent.

Patented July 7, 1914.

Application filed October 20, 1908. Serial No. 458,734.

To all whom it may concern:

Be it known that we, ALLAN M. HIRSH, a citizen of the United States, residing at Montclair, in the county of Essex and State of New Jersey, and JOHN C. MITCHELL, a citizen of the United States, and resident of Newport News, in the county of Warwick and State of Virginia, have invented certain new and useful Improvements in the Manufacture of Concrete Pipe, of which the following is a specification, reference being had to the drawings accompanying and forming part of the same.

Our invention relates to the manufacture of concrete pipe, more particularly for use in sewers, having part or all of its interior lined with vitrified or glazed brick, or equivalent material, and our chief object is to provide a simple, cheap and effective method for making pipe of this character.

The nature of the invention will be readily understood when explained in connection with the annexed drawings, and referring now thereto,

Figure 1 is a vertical section showing a section of pipe in process of formation. Fig. 2 is a plan view of the same. Figs. 3 and 4 are detail plan views. Fig. 5 is a detail sectional view showing a convenient way of supporting a reinforcing fabric in the pipe-mold when it is desired to make reinforced pipe. Fig. 6 is a longitudinal sectional view of a finished section of pipe.

In carrying out our invention a suitable mold is provided, for example that shown in the accompanying drawings. This mold is constructed for the formation of bell-end pipe of the ordinary shape, and consists of an inner part and an outer part. The former comprises a base 1, say of cast iron, and an inner form or core 2, preferably of stiff sheet metal. The outer part of the mold consists of a ring 3, formed to coöperate with the base 1 to give the desired "bell," and an outer casing 4.

The outer member of the mold being removed, the lining pieces 5, which, as previously stated, may be tiles, vitrified bricks, or other suitable material, are placed flat against the core or inner form 2 as shown in Figs. 1 and 2. These lining pieces may be of any convenient size, but are preferably rectangular, the longer in proportion to width the better. The lining may extend over the entire core, thus covering the

entire inner surface of the pipe when finished, but for pipe to be used in sewers it is usually unnecessary to have more than about half of the surface lined, for example, as illustrated in Fig. 6; the lined portion being the bottom of the sewer when the pipe sections are assembled in the trench.

In order to prevent any possible displacement of the lining pieces during the subsequent filling of the mold, the pieces may be held to the core by the simple expedient illustrated. For this purpose the core, before laying a course of lining pieces, is encircled with a band, such as a stout wire, 6, having a yielding section, for example 70 a coil spring 7. To lay the lining pieces the wire is drawn away from the core far enough to permit insertion of the pieces one after another, the resiliency of the elastic section of the band serving to hold each 75 piece firmly in position on the core while the succeeding pieces of the course are being laid. When the course is completed the elastic section of the band is removed, and the ends of the wire twisted tightly together 80 and laid flat against the core. The next course is then assembled in the same manner, and so on until the necessary number of courses are in place. It is to be understood, however, that the elastic section of 85 a band need not be removed immediately on completion of a course, or before the laying of the next, as all the elastic sections may be left in until the full number of courses is complete; or, if desired, the said 90 sections need not be removed at all, but it is preferable to take them out.

The lining being in place on the core, the outer part of the mold is placed in position, as shown in Figs. 1 and 2 concrete 95 is now deposited in the mold and tamped down. If the lining pieces are in the form of rectangular prisms, as will ordinarily be the case, V-shaped spaces will be left between contiguous pieces, as shown at 100 8 in Fig. 3, and the concrete, entering these spaces, takes a very firm grip on the blocks, anchoring them firmly in position. When the mold is full the top of the concrete is smoothed off with a trowel or other suitable implement.

After the concrete has set the mold sections are removed. The binding wires are thereby exposed on the unlined inner surface of the pipe, and can be stripped there- 110

from and cut off close to the brick work. A finished section of half-lined pipe then appears as in Fig. 6, and the lining will be found to be a permanent part of the structure. In fact, experience has shown that it is impossible to remove the lining except by chipping it out, so that the pipe-section can be said to be practically monolithic. The pipe can be manufactured in a factory, 10 and shipped to the point of use, more cheaply than the pipe can be constructed by the method heretofore in vogue.

Prior to our invention it has been customary to first construct the concrete portion, 15 in the trench, then to lay the lining bricks after the concrete had set. Such method is not only costly and troublesome, but also requires considerable time for the completion of the sewer, since the concrete part of 20 the structure cannot be built until the trench is dug, and the lining cannot be laid until the concrete part has set. The result is that brick or tile-lined concrete sewers are not resorted to except when the excessive 25 cost can be disregarded or where conditions demand that the pipe shall have the maximum resistance to erosion. On the other hand, pipe of standard sizes and shapes can be constructed by our method far in advance 30 of use and kept in stock, ready for laying as fast as needed, or the pipe can be made while the trench is being dug, with the result that the building of the sewer need take very little more time than the digging 35 of the trench.

The pipe constructed by our method can of course be "reinforced" if desired. For this purpose the base 1 of the inner mold-member can be provided with a groove or 40 slot 9, Fig. 5, in which the reinforcing fabric 10, of any suitable kind, may be set after the lining pieces are in place; said groove being in position to maintain the fabric preferably about midway between the lining 45 and the outer mold-member.

The procedure herein specifically described constitutes the preferred manner of practising our invention, but may be varied without departure from the proper scope 50 of the invention as set forth in the appended claims.

What we claim is:

1. The herein-described method of constructing a concrete pipe, which consists in 55 placing elastic wires around an inner cylindrical form or core, arranging the lining pieces against an arc or section of said core and binding the same thereon with said elastic wires, inclosing the inner form in 60 an outer form of the same contour and spaced therefrom, supporting a continuous reinforcing fabric between the inner and

outer cylindrical mold sections, and upon the base of the mold, and filling the spaces between the inner and outer mold sections 65 with concrete.

2. The herein described method of constructing a concrete pipe which consists in setting an inner substantially cylindrical form or core in substantially a vertical position, placing elastic wires around said cylindrical form or core, arranging the lining pieces against an arc or section of said vertically placed core and under said elastic wires whereby the pieces are held firmly in 75 position on the core, inclosing the inner cylindrical form in an outer vertically arranged form of substantially the same contour and spaced therefrom, and filling the spaces between the inner and outer mold 80 sections with concrete.

3. The herein-described method of constructing a concrete pipe which consists in setting an inner substantially cylindrical form or core in substantially vertical position 85 upon the base of the mold, placing elastic members around said cylindrical form or core, arranging the lining pieces against an arc or section of said vertically placed core and under said elastic members 90 whereby the pieces are held firmly in position on the core, inclosing the inner cylindrical form in an outer form of substantially the same contour and spaced therefrom, supporting a continuous reinforcing 95 fabric between the inner and outer mold sections and upon the base of the mold, and filling the spaces between the inner and outer mold sections with concrete.

4. The herein described method of constructing a concrete pipe which consists in setting an inner substantially cylindrical form or core in substantially vertical position, placing wires having yielding sections 100 connecting the ends thereof around said cylindrical form or core, arranging the lining pieces against an arc or section of said vertically placed core and under said wires whereby the pieces are held in position on 105 said core, removing the yielding sections and connecting the ends of the wires together, inclosing the inner cylindrical form in an outer form of substantially the same contour and spaced therefrom, supporting a continuous reinforcing fabric between the 110 inner and outer mold sections and upon the base of the mold, and filling the spaces between the inner and outer mold sections 115 with concrete.
